(57) **CLAIM**

The ornamental design for a shoe, as shown and described.

DESCRIPTION

FIG. 1 is a front perspective view of a shoe showing my new design;

FIG. 2 is a rear view thereof;

FIG. 3 is a side view thereof.

FIG. 4 is an opposite side thereof;

FIG. 5 is a top view thereof;

FIG. 6 is a rear perspective view thereof;

FIG. 7 is an opposite rear perspective view thereof; and,

FIG. 8 is an opposite front perspective view of FIG. 1.

The uneven-length broken lines immediately adjacent to the shaded areas define the bounds of the claimed design and form no part thereof. The even-length broken lines within the shaded areas, including the zig-zag shaped broken lines, represent stitching and form no part of the claimed design. The uneven-length broken lines depicting the remainder of the shoe show features that form no part of the claimed design.
